UNITED STATES PATENT OFFICE.

HARRISON D. McFADDIN, OF EAST ORANGE, NEW JERSEY.

DESIGN FOR A GLOBE FOR LAMPS, &c.

SPECIFICATION forming part of Design No. 29,494, dated October 18, 1898.

Application filed July 13, 1898. Serial No. 685,871. Term of patent 7 years.

To all whom it may concern:

Be it known that I, HARRISON DAWSON McFADDIN, a citizen of the United States, residing at East Orange, in the county of Essex and State of New Jersey, have invented and produced a new and original Design for a Globe for Lamp or Gas Burners, of which the following is a specification, reference being had to the accompanying drawings, which

- o form a part thereof, and in which—

Figure 1 is a plan view of my newly-designed globe for lamp or gas burners, and Fig. 2 a central vertical section thereof.

As shown in the drawings, the leading or material feature of my newly-designed globe for lamp or gas burners consists of an enlarged portion A, which is provided centrally of the bottom with an annular upwardly and inwardly directed groove B, the inner walls o of which consist of an annular downwardly-directed flange or rim C, which constitutes the base proper of the globe, by which it is connected with a lamp or gas burner.

The outer portion D of the part A of the

globe is convex in cross-section on its lower side and is slightly above or on a higher plane than the bottom of the flange or rim C, and the upper portion of the part A is contracted to form a neck E, which is provided with an annular bead F at about the middle thereof, and above which said neck is expanded or bell-shaped in form, as shown at G, and the entire globe is symmetrical in form and attractive in appearance.

Having fully described my invention, I claim as new and desire to secure by Letters Patent—

The design for a globe for lamp or gas burners as herein shown and described.

In testimony that I claim the foregoing as my invention I have signed my name, in presence of the subscribing witnesses, this 5th day of July, 1898.

HARRISON D. McFADDIN.
